UNITED STATES PATENT OFFICE.

HARRY P. FOWLER, OF WATERBURY, CONNECTICUT, ASSIGNOR TO THE WATERBURY TOOL COMPANY, OF WATERBURY, CONNECTICUT, A CORPORATION OF CONNECTICUT.

POWER-TRANSMITTING DEVICE.

Application filed June 9, 1927. Serial No. 197,555.

This invention relates to power transmitting devices, and particularly to power transmissions for plants, in which a plurality of machines or sections of a machine are driven simultaneously from a main or primary source of power. For example, in paper making plants, it is the custom to use what is known as a sectional paper making machine, which machine comprises a plurality of sections, each of which sections performs a certain step of the process of finishing or completing the paper from the pulp to the completed article. It is preferable to drive these machines from some main source of power, to provide means for varying the speed of the machine as a whole, and also to incorporate in the driving means some provision for varying the speed of each section of the machine within comparatively small limits relatively to the other sections. It is very desirable to be able to regulate both the speed of the machine as a whole, as well as the relative speeds of the sections quickly, accurately and positively in order that when changes are made from one grade of paper to another, the desired grades of paper may be instantly obtained without waste or undue delay or breakage of the sheet.

The principal object of this invention is to provide a new and improved power transmitting device, particularly adapted for use in plants of the character above set forth, which device will be capable of securing the desired results described above.

Many different types of power transmitting devices have been heretofore employed for use in connection with machines of the character to which this invention relates, the devices most commonly employed being of the taper cone, pulley belt, drive character. The use of hydraulic drives in connection with paper making machinery has been recognized as presenting many advantages, because of the marked adaptability of such drives for obtaining very gradual changes of speed control as well as accurate adjustment thereof.

In my co-pending application Serial #132,914, I have shown and described an example of a hydraulic gear drive installation for a sectional paper making machine. Considered in its more specific aspects, the present invention is an improvement upon the installation shown in said application.

In accordance with the present invention,

as well as with the invention disclosed in my prior application, I prefer to employ hydraulic gears or driving mechanisms of the type known as "Waterbury gears" such as manufactured by the Waterbury Tool Company of Waterbury, Connecticut, and disclosed in various patents, for instance United States Letters Patent of Harvey D. Williams #925,148, granted June 15, 1909. Such hydraulic gears are well known and the detail constructions thereof form no part of the present invention. It will be sufficient to state that they consist of a pump section and a motor section, each of which consists of a rotary barrel secured to a shaft, which in the pump section, is driven from any suitable source of power; and, in the motor section is suitably coupled to the part to be driven. Each rotary barrel has formed therein a plurality of cylinders parallel with its respective shaft and in which reciprocate pistons. Said pistons are connected with a swash plate, the swash plate of the pump section being adjustable to different angles of inclination. For the purpose of varying the stroke of the pistons and therefore the output, or the amount of fluid delivered by the pump for each revolution of the rotary barrel, the inclination of the swash plate of the pump is adjusted, preferably by the rotation of a control shaft operatively connected with a tilting box in which the swash plate is rotatably mounted, while the angle of inclination of the swash plate of the motor section is preferably fixed. When the tilting box and swash plate of the pump are perpendicular to the driving shaft thereof, or in the "neutral position", the pump pistons have no stroke and no fluid is pumped. The pump section is operatively connected to the motor section through inlet and outlet ports, common to both sections, and provided in a central dividing plate which separates the two sections. As the control shaft is rotated to tilt the swash plate, the stroke of the pump piston and the output of the pump is increased as the angle of inclination increases. Increase in the output of the pump produces a corresponding increase in the speed of rotation of the driving shaft of the motor, all as set forth more fully in the Williams patent above referred to.

A satisfactory and preferred embodiment of my invention is illustrated in the accompanying drawings, in which Fig. 1 is a

plan view of a power transmitting device constructed in accordance with the principles of the present invention and showing diagrammatically a plurality of sections of

- 5 a paper machine, each of which is driven by a hydraulic speed gear; Fig. 2 is a section taken substantially on the line 2—2 of Fig. 1, while Fig. 3 is a section through one of the hydraulic driving units.
- 10 As shown in the drawing, the numerals 10, 11, indicate sections of a paper machine, each of which is driven by a shaft 12, connected with the driving shaft of the motor section 13 of a hydraulic variable speed
- 15 gear unit 14, one or more flexible couplings 15 preferably being interposed between the paper machine section and the driving shaft of the motor.

Each variable speed gear unit also includes a pump section 15, having a control shaft 16, the lower end of which is suitably connected with the swash plate 17 of the pump. The control shaft 16 is threaded for a portion of its length to engage within 25 a nut 18, rotatably mounted in suitable bearings provided in the pump casing. The nut 18 projects outwardly beyond the pump casing and has secured to its upper end a bevel gear 19 with which meshes a co-operating gear 20 secured to one end of a follow-up shaft 21, the latter extending in parallelism with and above the axis of the speed gear unit, and having its other end supported in bearings provided in brackets 30 or standards 22, 23. Secured to the follow-up shaft 21 between the brackets 22, 23, is a tapered cone pulley 24, about which, and a similar, but oppositely tapered, pulley 25, a belt 26 is trained, the cone pulley 25 being 35 secured to the shaft 12 driven by the motor section 13.

The control shaft 16 projects upwardly beyond the follow-up shaft 21 and its upper end fits slidably but non-rotatably within a 40 bevel gear 27, meshing with a bevel gear 28, secured to a master control shaft 29. The master control shaft extends along the entire side of the machine and has connected to one end thereof a hydraulic variable speed gear unit 30 of the same type as the gear unit 14. Each section of the paper machine is provided with a gear unit 14 having a control shaft 16, follow-up shaft 21, variable speed belt and cone pulley drive 45 and associated parts, and each pump control shaft 16 is operatively connected with the master control shaft 29 by means of the bevel gears 27, 28.

The input, or pump section, shaft 31 of 50 the speed gear unit 30 is driven at a constant speed by any suitable means, and the speed of rotation of the master control shaft 29 which forms the output shaft of said speed gear 30 is adapted to be varied 55 by adjusting the control shaft 32 of the

pump section of said speed gear 30 by means of a manually operatable hand wheel 33 secured to the upper end of said control shaft 32.

The input shaft 35 of each of the hydraulic speed gear units 14 is preferably connected by means of a flexible coupling 36 with an axially aligned shaft 37, to which is secured a bevel gear 38. Each of the gears 38 is driven by means of a bevel gear 39, secured to a main power shaft 40 which is driven by an electric motor 41 rotating at a constant speed.

The operation of the installation is as follows: The electric motor 41 which, as assigned, is a constant speed motor, constitutes the power source for driving the machine as a whole. Let it be assumed that all of the parts are at rest and that the control shafts for all of the speed gear units 14 are in neutral position. If now the motor 41 be rotated it will rotate, through the main driving shaft 40, bevel gears 39, 38 and shafts 37, the input shafts of the pump sections 15 of all of the speed gear units 14 at a constant uniform speed, but no rotation of the shafts 12 of the motor sections 13 of said units will occur, because, as assumed, all of the control shafts 16 are set at "neutral". If the speed gear unit 30 is now rotated and its control shaft 32 is manipulated to produce any desired speed of rotation of the master control shaft 29, which it will be remembered is the output shaft of the speed gear unit 30, the control shafts 16 of all of the speed gear units 14 will be rotated from the neutral position, thereby to cause the gear units 14 to become operative. The speed of rotation of the output shafts of all of the gear units 14, effected by the rotation of the master control shaft 29, obviously will be equal and 100 all of the sections of the machines will be driven at the same speed provided all of the belts 26 are set in the same position. As each of the shafts 12 is rotated, its rotation 105 will be communicated through the cone pulleys 24, 25 and belt 26 to its respective follow-up shaft 21 at a certain speed ratio determined by the setting of the belt shifted 26 for each respective belt. Rotation of the follow-up shaft 21 causes the nut 18 in engagement with the control shaft 16 of each respective pump section to be rotated in the same direction of rotation as the control shaft 16 is rotated through the medium of the master control shaft 29. There will be a slight lag or dwell before the nut 18 reaches its full speed of rotation because of the fact that the rotation of the shafts 12 is accomplished through the medium of the fluid pumped by each pump section 15 to its motor section 13.

If it be assumed that the belt 26 is set to produce a speed of rotation of the follow-up shaft 21 equal to the speed of rotation of its respective shaft 12 a condition 110

115

120

125

130

will soon be reached when the nut 18 and its respective control shaft 16 will be rotating at the same speed, which speed is determined by the speed of rotation of the master control shaft 29. The differences in speed between each control shaft 12 and its respective follow-up shaft 21 secured by the adjustment of the belt 26 are comparatively slight. The speed of the machine as a whole is, as 10 will be readily understood, determined by the speed of rotation of the master control shaft 29 the speed of rotation of which can be varied to secure any desired speed say, for example, one revolution per minute up to the 15 full speed of the electric motor or other driving means employed for driving the speed gear 30, and the changes in the speed of rotation of the master control shaft 29 may be made as gradually as desired. No matter 20 what the speed of rotation of the master control shaft 29 may be, the speed of rotation of all of the shafts 12, neglecting slight differences due to the setting of the belts 26 will obviously be equal to the speed 25 of rotation of the master control shaft. In the last analysis, however, the rotation of each shaft 12 is utilized to effect its own speed of rotation through the medium of the pulleys 24, 25, belt 26, follow-up 30 shaft 21 and nut 18. It will be seen that it will be possible with the installation herein disclosed to secure, by slight adjustments of the belts 26, a speed of rotation of all of the machine sections that will be absolutely 35 uniform or that the most minute differences in the relative speeds of different machine sections may be obtained, and maintained, to secure the proper draw between the sections.

40 Due to the fact that the main power source is the electric motor 41, which is put in rotation at its full speed before the master control shaft 29 is rotated to move the control shafts 15 from "neutral", and also to the fact 45 that the application of power for starting the machine sections is made through fluid pressure means, it is not necessary to employ an electric motor which will have a high starting torque. In addition the invention 50 enables two or more speed gear units to be applied to any one section of the paper machine where greater power or torque may be required than for other sections. The use of hydraulic speed gears enables the machine 55 to be run very slowly for "threading in" the paper and after the paper is threaded in, the control shaft 32 of the speed gear 30 may then be set to secure the desired speed of rotation of the machine as a whole. It will be 60 understood that a suitable indicating dial may be employed for the control shaft 32 so that said shaft may be set instantly to secure the desired speed of the machine.

If it is found necessary or desirable in 65 order to compensate for "draw" of the paper,

and to change the speed of any particular section of the machine relatively to that of the other sections, the belt shifter 26^a of such section may be adjusted in the proper direction to accelerate or retard by slightly 70 changing the speed ratio between the follow-up shaft 21 and the driving shaft 12 of such section.

It will be understood that the speed changes, by means of the adjustment of the 75 belt shifters, is but comparatively slight.

It will also be understood that the speed of the machine as a whole will be controlled by the setting of a single, readily manipulated member, namely, the manually operable handle 38, adjustment of which controls the speed of the master control shaft 29 for producing any desired speed within the limits of the installation. Owing to the fact 80 that the drive is hydraulic, the speed changes of the machine as a whole, as well as the speed changes between the respective sections thereof, can be made very gradually without producing any abrupt or sudden 85 jerks, such as would tend to cause rupture or tearing of the paper. In addition, the speed adjustments of the entire machine, as well as each section thereof, can be made 90 with the greatest accuracy of control.

While I have illustrated and described the 95 invention as applied to a sectional paper making machine, it is to be understood that the principles of the invention are not limited in their application to the particular machine selected for the purpose of illustration herein, but that they may be employed with many different types of machines and in many different relations. Likewise, it 100 will be understood that various changes, variations and modifications may be made 105 without departing from the principles of the invention.

I claim:

1. The combination with a plurality of machine units adapted to perform successive steps of a continuous operation upon material treated by such units, of a plurality of driving units for each of said machine units, characterized by each of said driving units consisting of a hydraulic variable 110 speed gear having a control shaft adapted to be rotated to vary the driving speed of said speed gear, a master control shaft for simultaneously actuating all of said control shafts, and means driven by the driving 115 shaft of each respective speed gear for counteracting the adjustment of its respective control shaft produced by rotation of the master shaft, said means including an adjustable device for varying its effect.

2. The combination with a plurality of machine units adapted to perform successive 120 steps of a continuous operation upon material treated by such units, of a plurality of driving units for each of said machine units,

characterized by each of said driving units consisting of a hydraulic variable speed gear having a control shaft adapted to be rotated to vary the driving speed of said speed gear,
 5 a master control shaft for simultaneously actuating all of said control shafts, and means driven by the driving shaft of each respective speed gear for counteracting the adjustment of its respective control shaft
 10 produced by rotation of the master shaft, said means including a follow-up shaft, operative connections between said follow-up shaft and its respective control shaft, and a variable speed driving connection between
 15 said follow-up shaft and the driving shaft of its respective speed gear.

3. The combination with a plurality of machine units adapted to perform successive steps of a continuous operation upon material treated by such units, of a plurality of driving units for each of said machine units, characterized by each of said driving units consisting of a hydraulic variable speed gear having a control shaft adapted to be
 20 adjusted to vary the speed of said gear, a master control shaft and connections therefrom to each of said speed gears, means for driving said control shaft including a device for adjusting the speed thereof, a follow-up shaft for each of said speed gears and driving connections between said follow-up shaft, the driving shaft of its respective speed gear and the control shaft thereof, said driving connections including an adjustable
 25 variable speed device.

4. The combination with a plurality of machine units adapted to perform successive steps of a continuous operation upon material treated by such units, of a plurality of driving units, one for each of said machine units, and a main driving device for driving all of said driving units in unison, characterized by each of said driving units consisting of a hydraulic variable speed gear, having an adjustable control shaft, a rotatable nut in which said control shaft is rotatably mounted, a follow-up shaft for each of said speed gears operatively connected with the driving shaft of its respective
 40 gear and with said nut, a variable speed device interposed between said driving shaft and said nut, and a master control shaft operatively connected with all of the control
 45 shafts of said speed gears.

5. The combination with a plurality of machine units adapted to perform succes-

sive steps of a continuous operation upon material treated by such units, of a plurality of driving units, one for each of said machine units, and a main driving device for driving all of said driving units in unison, characterized by each of said driving units consisting of a hydraulic variable speed gear, having an adjustable control shaft, a rotatable nut in which said control shaft is
 50 rotatably mounted, a follow-up shaft for each of said speed gears operatively connected with the driving shaft of its respective gear and with said nut, a variable speed device interposed between said driving shaft and said nut, and a master control shaft operatively connected with all of the control
 55 shafts of said speed gears, and a variable speed hydraulic gear for driving said master control shaft.

6. The combination with a plurality of machine units adapted to perform successive steps of a continuous operation upon material treated by such units, and a plurality of driving units, one in each of said machine units, of a main power driving device of uniform speed, a master control of adjustable speed for regulating the speed of all of said driving units in unison, and an independent controlling device of adjustable effect for each of said driving units, each of said independent devices being connected with and driven by the driving shaft of its respective driving unit whereby the rotation of the driving shaft of each unit is
 60 employed to control its own speed.

7. The combination with a plurality of machine units adapted to perform successive steps of a continuous operation upon material treated by such units, and a plurality of driving units, one for each of said machine units, of a main driving shaft, a power device of constant uniform speed connected with said main driving shaft, gearing connecting said main driving shaft with each of said driving units, a controlling device for each of said driving units for regulating the speed thereof, a master control shaft and connections therefrom to each of said controlling devices, a driving device of adjustable effect for actuating said master control shaft, and a follow-up control for each of said driving units interposed between the driving shaft of its respective unit and the said controlling device in said unit.

In testimony whereof I have hereunto set my hand.

HARRY P. FOWLER.
